Atty.

UNITED STATES PATENT OFFICE.

FRANK B. SMITH, OF MAYWOOD, ILLINOIS.

CLOTHES-WRINGER ATTACHMENT.

1,307,217.

Specification of Letters Patent. Patented June 17, 1919.

Application filed November 27, 1917. Serial No. 204,182.

To all whom it may concern:

Be it known that I, FRANK B. SMITH, citizen of the United States, residing at Maywood, in the county of Cook and State 5 of Illinois, have invented certain new and useful Improvements in Clothes-Wringer Attachments, of which the following is a specification.

This invention relates to improvements in 10 clothes wringer attachments, and one of the objects of the same is to provide an improved device of this character which is adapted to be readily attached to wringers by means of which attachment the 15 clothes may be readily and conveniently supplied to the rolls, without endangering the fingers or hand of the operator.

A further object is to provide an improved 20 device of this character embodying an endless conveyer belt adapted to be passed between the wringer rolls and to extend on opposite sides thereof, and to which belt a traveling movement is adapted to be imparted by the friction of the wringer rolls 25 thereon.

Heretofore in devices of this character considerable difficulty has been experienced in that the conveyer belt becomes twisted so that it will not run smoothly, thereby 30 causing great annoyance and often times considerable inconvenience. To overcome these difficulties and objections and to provide an improved device of this character, having means whereby the conveyer belt 35 will be maintained flat and held straight against any twisting, folding or wrinkling action, is another object of the present invention.

A further object is to provide improved 40 means whereby this device may be readily and detachably applied to a drain board of any wringer, within certain limits, and having means whereby the tension of the conveyer belt may be varied at will.

To the attainment of these ends and the accomplishment of other new and useful objects as will appear, the invention consists 45 in the features of novelty in substantially the construction, combination and arrangement of the several parts hereinafter more fully described and claimed and shown in the accompanying drawing illustrating this invention, and in which—

Figure 1 is a side elevation of an improved device of this character, constructed 55 in accordance with the principles of this

invention, showing the same applied to a wringer drain board with the wringer rolls in section.

Fig. 2 is a sectional view taken on line 60 2—2, Fig. 1.

Fig. 3 is a sectional view taken on line 3—3, Fig. 1.

Fig. 4 is a detail perspective view of one 65 of the securing means.

Fig. 5 is a detail view of a modification.

Referring more particularly to the drawing, the numeral 10 designates a drain board of a wringer and the numerals 11 and 12 designate the wringer rolls between which 70 one end of an endless flexible band 13 is adapted to pass. This band may be constructed of any suitable material such as fabric or the like and is of a width substantially equal to the length of the active portions of the wringer rolls 11, 12. This endless belt passes over pulleys or rollers 14, 15 and when in position, the other run of the endless belt will pass beneath the lower wringer roll. Each of the rollers 14, 15 80

are provided with suitable trunnions 16 secured in their extremities and comprise a body portion adapted to be inserted in the end of the rollers. Each of the trunnions is provided with a collar 17 and a head 18, 85 and which collar is located a short distance from the head so that when the trunnion is fastened in position, the collar 17 will maintain a headed end 18 projecting beyond the end of the roller. Obviously any 90 form of trunnion may be employed. Each of the rollers 14, 15 is supported at its ends in suitable bearings and arranged adjacent each end of the roller is a suitable supporting structure embodying a main portion 19, 95 one end of which is shaped to form an upwardly projecting portion 20 having a series of open slots or recesses 21, forming bearings into which the trunnions are adapted to be inserted and these bearings 100

21 are arranged preferably above each other so that the position of the roller may be varied with respect to the drain board 10. This will permit the device to be accommodated to wringers of different sizes. 105

Coöoperating with the main member 19 of the support is another member 22 having similar open bearings 23 and is connected with the main member by means of a suitable pivot 24. The free end of the member 110 22 projects for a short distance beyond the pivot as at 25 and the end 26 of the main

member 19 is deflected so as to stand adjacent the end 25 of the member 22. A suitable adjusting device 27, such as a thumb screw is adjustably mounted in the end 26 5 of the member 19 and the free end of the screw abuts the end 25 of the member 22, so that by adjusting the screw 27, the member 22 will be moved about its pivot and thereby the tension of the endless band 13 10 may be varied.

This device is adapted to be removably secured to the drain board 10 in any suitable manner, such as by means of fastening hooks 28 which pass through suitable slots 29 in 15 the member 19 and have a threaded extremity adapted to receive a nut 30. The slots 29 permit the fastening hooks 28 to be adjusted to accommodate them to drain boards of different widths.

20 With this improved construction, it will be manifest that the device being supported by the drain board, the whole mechanism can be tilted in one direction or the other according to the adjustment of the drain 25 board and inasmuch as the wringer rolls have frictional contact with one run of the endless belt, the belt will be driven by the wringer rolls.

When the direction of operation of the 30 wringer rolls is reversed or changed, it is obvious that the drain board may be shifted which will correspondingly shift the attachment.

In order to hold the band 13 flat and 35 prevent the same from twisting, wrinkling or buckling during the operation, which would seriously interfere with its operation, suitable means have been provided to that end, and constitute primarily a reinforcing 40 rib 31 which may be constructed of any suitable material, and one of these ribs is preferably incased in a portion of the band to extend along the edges thereof and is of greater thickness than the band. The rollers 45 14, 15 are provided with circumferential recesses 32 adapted to receive these ribs.

It will thus be manifest that the ribs 31 and recesses 32 will cooperate to hold the band at all times straight and flat.

50 This improved device is adapted to be attached to any form of wringer but is particularly advantageous with power wringers.

In use, the articles which are to pass between the wringer rolls 11, 12 are placed 55 upon the endless band 13, and as the wringer rolls rotate, the band 13 will be operated or caused to travel so that the articles will be moved toward the wringer rolls. This will protect the fingers and hands of the 60 operator as it is not necessary for the operator to feed the articles to the rolls 11, 12.

All that is necessary is to place them upon the endless band and they will be carried forward to the rolls by the operation of the 65 band.

In the modified form of the invention shown in Fig. 5 the lower wringer roll 12 is provided with a recess 34 into which the ribs 31 project and travel, and in this form of the invention is provided as an additional 70 means for holding the belt or band 13 flat.

The band 13 is preferably formed by securing the ends of the element together in any suitable manner and with any suitable fastening means, so as to permit this device 75 to be readily applied to wringers now manufactured, but it is obvious that the band may be also manufactured as a continuous or endless band.

What is claimed as new is—

1. A clothes wringer attachment, embodying an endless flexible band, means for supporting said band from the wringer drain board, and embodying spaced rollers over which the band travels, said rollers being 85 adapted to be located on opposite sides of the wringer rolls, one of the runs of the said band passing between the wringer rolls whereby the band will be driven by the friction of the wringer rolls, and co-operating 90 means on the band and the first recited rollers intermediate the ends of said rollers for maintaining the said band against twisting and wrinkling during the travel of the band. 95

2. A clothes wringer attachment, embodying an endless flexible band, means for supporting said band from the wringer drain board, and embodying spaced rollers over which the band travels, said rollers being 100 adapted to be located on opposite sides of the wringer rolls, one of the runs of the said band passing between the wringer rolls whereby the band will be driven by the friction of the wringer rolls, co-operating means 105 on the band and the first recited rollers intermediate the ends of the rollers for maintaining the said band against twisting and wrinkling during the travel of the band, and means for varying at will the tension of the 110 said band.

3. A clothes wringer attachment, embodying an endless flexible band, means for supporting said band from the wringer drain board, and embodying spaced rollers over which the band travels, said rollers being adapted to be located on opposite sides of the wringer rolls, one of the runs of the said band passing between the wringer rolls whereby the band will be driven by the friction of the wringer rolls, means extending lengthwise of the band for maintaining the band straight, and means on the rollers co-operating with the last recited means. 115 120

4. A clothes wringer attachment embodying an endless flexible band, means for supporting said band from the wringer drain board, and embodying spaced rollers over which the band travels, said rollers being adapted to be located on opposite sides of 125 130

the wringer rolls, one of the runs of the said band passing between the wringer rolls, whereby the band will be driven by the friction of the wringer rolls, reinforcing means 5 extending lengthwise of the band and projecting beyond the surface of the band, and grooves in the rollers intermediate the ends of the latter and in which grooves the said reinforcing means projects to maintain the 10 band flat and straight during its travel.

5. A clothes wringer attachment embodying an endless flexible band, rollers over which the band travels, coöoperating means on the band and rollers intermediate the 15 ends of the rollers for maintaining the band flat and straight while traveling, one run of the band passing between the wringer rolls to be driven thereby, means for supporting the attachment from the wringer drain 20 board and embodying supporting means for the band rollers whereby the attachment will be shiftable with the drain board, and means for varying the tension of the said band.

6. A clothes wringer attachment embodying an endless flexible band, rollers over 25 which the band travels, coöoperating means on the band and rollers intermediate the ends of the rollers for maintaining the band flat and straight while traveling, one run of the band passing between the wringer rolls to be driven thereby, means for supporting the attachment from the wringer drain 30 board and embodying supporting means for the band rollers, and means whereby the 35 rollers may be adjusted with respect to the supporting means and the wringer drain board.

7. A wringer attachment embodying a support, said support embodying two adjustably connected elements, spaced rollers adjustably mounted in said elements, an endless band passing over said rollers, one run of the band passing between the wringer rolls, to be frictionally driven thereby, 45 means securing the support to the wringer drain board, and means for adjusting the elements of the support to vary the tension of the band.

8. A wringer attachment embodying a 50 support, spaced rollers mounted upon the

support, an endless band passing over said rollers, one run of the band passing between the wringer rolls, to be frictionally driven thereby, and a rib extending along each edge of the band, said rollers having grooves intermediate their respective ends and into which grooves the ribs project for holding the band flat and straight during operation. 55

9. A wringer attachment embodying a support, spaced rollers adjustably mounted upon the support, an endless band passing over said rollers, one run of the band passing between the wringer rolls, to be frictionally driven thereby, and a rib extending along each edge of the band, one of the wringer 60 rolls having grooves intermediate its ends and into which grooves the ribs project to hold the band flat and straight during operation. 65

10. A wringer attachment embodying pivotally connected elements having spaced bearing portions, said portions having a plurality of open bearings, rollers, trunnions at the ends of the rollers adapted to be inserted in the said open bearings, an endless band 70 passing over the rollers, one of the runs of the band passing between the wringer rolls, an adjusting device contacting with portions of the said elements for relatively adjusting them to vary the tension of the band, and 75 means for detachably securing the device to the drain board of the wringer. 80

11. A clothes wringer attachment embodying an endless flexible band, means for supporting the band from a wringer board, one 85 run of the band passing between the wringer rolls, and means for maintaining the band against twisting or wrinkling during the traveling of the band, the last recited means embodying a roller over which the band 90 passes, said roller being of a length to extend entirely across the band and having a groove intermediate its ends, and a rib extending lengthwise of the band and adapted to travel in said groove. 95

In testimony whereof I have signed my name to this specification, on this 21st day of November, A. D. 1917.

FRANK B. SMITH.
